UNITED STATES PATENT OFFICE.

CHARLES UEBELMESSER, OF NEW YORK, N. Y.

STEAM BOILER.

Application filed November 6, 1925. Serial No. 67,245.

While my improvements are applicable to the construction of steam boilers generally, they are especially adapted to steam generating apparatus for use in automobiles, and for analogous purposes, where a continuous, rapid supply of live steam is a desideratum,—the invention consisting in the specific combination, arrangement and construction of the component parts and appurtenances of the boiler herein described and claimed; and distinctive features being the configuration and nesting of the boiler tubes and their adaptability to replacement; the means employed for reinforcing the walls of the generative tube chamber; compactness of structure; and other incidental advantages attained, all as hereinafter fully set forth.

In the accompanying drawings I illustrate a practical embodiment of the essential elements of my invention in a substantially cylindrical upright boiler of the character designated, although I do not restrict myself to the identical form and construction of component parts of the apparatus shown by way of exemplification, since changes may be made in minor details, and equivalent mechanical expedients resorted to with like results, and without departing from the spirit and intent of my invention in this respect.

With this understanding:

Fig. 1, represents a vertical section taken upon plane of line 1—1, Fig. 2;

Fig. 2, is a horizontal section taken upon plane of line 2—2, Fig. 1;

Fig. 3, is a plan of the top of the boiler section, broken away in part to show interior construction;

Fig. 4, is a horizontal section taken upon plane of line 4—4, Fig. 1.

The heater H, forming the lower portion of the combustion chamber C, may be of any suitable or desired type, said combustion chamber C, constituting the lower portion of the generative chamber G, in which, the feed water heating coil f, and generator tubes g, g, are located.

The feed water heating coil f, is positioned against the inner side of the cylindrical wall b, of the generative chamber G, which also constitutes the inner wall of the boiler water space w, as will be seen by reference more particularly to Figs. 1 and 2, of the drawings, thus bracing and reinforcing said partition wall b, against expansive strain and pressure incidental to steam gen-

eration. The upper end of the feed water heating coil f, communicates with an inlet pipe i, as shown in sectional detail on the left side of Fig. 1, the upper end of said inlet pipe i, being connected with a water supply pipe s. The lower end of the feed water heating coil f, communicates with the annular hot water space w, formed between the wall b, of the generative chamber G, and the outer shell b', of the boiler, through the medium of the outlet duct k, as shown in sectional detail on the lower right side of Fig. 1, the level of hot water in said boiler space w, being prescribed by a drain stand pipe z, shown in elevation in the left portion of Fig. 1. On the same side of said Fig. 1, the inlet duct e, to one of the lower horizontal generative tubes g, is shown in sectional detail, it being understood that a like inlet duct e, is provided for each of the several horizontal generative tubes g, connecting them with the boiler water space w. Each of said generative tubes terminates in an outlet extension g', which projects into an exit stand pipe p, extending through the drying chamber D, above the top plate b^a, of the generative chamber G, and the top plate b^b, of the boiler, as illustrated in sectional detail on the upper right side of Fig. 1, of the drawings, each of said exit stand pipes p, being formed with an outlet p', opening into said drying chamber D.

To facilitate detachable connection between the outlet extension g', of each generative tube g, and its exit stand pipe p, said extension g', is formed with a welded head g², fitting within its exit stand tube p, said head g², being formed with a perforated cross end member which is also female screw threaded for connection with a coupling screw bolt p³.

As will be understood by reference to Fig. 2, of the drawings, there are three generative tubes g, of serpentine shape, in each horizontal layer thereof, each tube being supported at one extremity by its inlet duct e, and at its other extremity by its exit stand pipe p, both heretofore referred to, the medial portions of each of said generative tubes g, being supported by and on a rest plate r, which is supported in turn on a suspender bolt r', the upper portion of which is screw-threaded for engagement with a nut b⁴, integral with the top plate b^a, of the generative chamber G. There is an individual tray rest plate r, for each of

the six layers of return bend serpentine generative tubes g , of which latter there are three in each layer, and each tray rest plate r , is formed on its upper side with three pockets or depressions r^2 , each for the reception and support of the central bight or return convolution g^x of a serpentine generative tube g , where it doubles upon itself, as shown in said Fig. 2.

10 It will thus be seen in this connection, and considering Figs. 1 and 2, of the drawings conjointly, that the medial return bends g^x , of the generative tubes g , are located, substantially, in the centre of the generative chamber G , where they are exposed to a maximum of heat incidental to the passage of the products of combustion from the combustion chamber C , through said generative chamber G , on their way to the outlet tubes 15 b^e , interposed between and connected with the top plate b^s , of the generative chamber G , and the top plate b_s , of the boiler, said outlet tubes b^e , extending through the drying chamber without communication therewith and discharging the products of combustion into the horizontal flue b^o , from which they are withdrawn through the vertical exit flue b^r , as indicated in Fig. 1, of the drawings in which figure only two of the 20 outlet tubes b^e , are shown as of full length, the others being broken away to more clearly show the stand pipes p , positioned in the drying chamber D .

It will be noted by referring to Fig. 2 25 that each generative tube g is of the same construction or configuration and consists of a pair of parallel irregularly shaped sinuous lengths or coils which are connected at one end by the return bend portion g^x , and that 30 the distance from the inlet e to the return bend portion is greater than the distance from the return bend to the exit g' , thus insuring a rapid flow of the steam from the highly heated return bends to the exit g' . 35 It will also be noted that the outlets and inlets are arranged at equally spaced intervals around the circumference of the boiler, and that the three pairs of outlets and inlets for the three coils which comprise each horizontal layer of elements are equally spaced 40 about the boiler. It will be understood that the tubes g of each horizontal layer are similar in construction and arrangement and correspond with the showing of Fig. 2 except that the outlets and inlets of each layer 45 obviously are out of vertical alignment with the other layers, as a result of this, although every tube g is of the same shape and size. The coils and return bends are out 50 of vertical alignment, so that a tortuous passage for the furnace gases about the coils is provided and the coils of a lower horizontal series do not completely screen those above.

The steam is withdrawn from the latter

through an outlet b^s , in the top plate b^s , of the boiler, and thence conducted by a pipe b^o , to the superheating coil S , located between the combustion chamber C , and the generative chamber G , the form of said superheating coil S , being shown in detail more particularly in Fig. 4, of the drawings, s , representing the inlet duct, and s' , the outlet duct of said coil S .

By the form and arrangement of component parts of my steam generating apparatus I attain and combine compactness of structure with a high degree of efficiency, since the heat of the products of combustion is utilized to a maximum degree, while at the same time, ample provision is made for the replacement of parts, particularly the individual generative tubes g , with a minimum of disturbance or other parts of the apparatus. Furthermore, the positioning of the feed water heating coil f , directly against the inner surface of the wall b , of the generative chamber G , is a decided improvement in that it is not only thus practically out of the way, but also functions as 85 a reinforcement of said partition wall b , as hereinbefore stated.

The drain stand pipe z , is of importance in maintaining a water level of sufficient height in the boiler space w , to insure the maintenance of a full supply of water in the generative tubes g . By constructing the steam generating part of the boiler of a large number of relatively short independent tubes or elements a much more rapid steam 100 generation and a much quicker separation of the steam from the water is secured than with constructions wherein a single length of pipe is coiled to provide several horizontal layers which form part of a single 105 coil. In addition, if a tube should burn out the replacement of a relatively short length of tubing obviously involves a much smaller replacement expenditure.

What I claim as my invention and desire 110 to secure by Letters Patent, is:—

1. In a steam boiler, a steam generating tube having a pair of parallel sinuous coils connected by a return bend and having an outlet and an inlet, said outlet and inlet being spaced from each other and from said return bend to provide three widely separated supporting points, the distance from said inlet to said return bend being greater than the distance from said bend to said outlet and the sinuous configuration of said coils being such that said tube may be placed in nested intervoluted spaced relationship with a similar tube.

2. In a steam boiler, a plurality of steam 125 generative elements arranged in superposed horizontal layers, each of said layers consisting of a plurality of similar steam generating coils, each of said coils consisting of a pair of parallel sinuous lengths con-

nected by a return bend and said coils being arranged in intervoluted spaced relationship with the return bends thereof grouped in the central portion of the boiler.

- 5 3. In a steam boiler, a steam generator consisting of a plurality of similar tubes, each consisting of a pair of parallel sinuous coils connected by a return bend and terminating in an outlet and an inlet, said 10 tubes being arranged to form a plurality of horizontal layers each of said layers consisting of a plurality of said tubes arranged in intervoluted spaced relationship, the outlets and inlets of each layer of tubes being 15 equally spaced about the boiler adjacent to the inner wall thereof and the return bends of each layer being grouped in the central part of the boiler.
4. A steam boiler as set forth in claim 3 20 in which the outlets and inlets for all the tubes are arranged circumferentially about the boiler at equally spaced intervals and

so that the coils and return bends of each horizontal layer are out of vertical alignment with those of the other horizontal 25 layers.

5. A steam boiler of the type wherein a plurality of coils of tubing arranged in horizontal layers form the steam generative element of the boiler, each horizontal layer 30 being formed of a plurality of separate sinuous tubes of similar shape and size arranged in intervoluted relationship, characterized by each separate tube being provided with a return bend located adjacent 35 to the center of the boiler and a supporting device common to all of said tubes being provided with means to engage each return bend portion of each tube, and to hold the tubes of each horizontal layer in properly 40 spaced relationship to those of the adjacent layers.

CHARLES UEBELMESSE.
